FLIP-TOP INSTRUMENT CABINET Allen B. Hehs, Mayfield Heights, Ohio, assignor to Bud
Radio Incorporated, Willoughby, Ohio

Filed May 12, 1971, Ser. No. 142,848

Term of patent 14 years

Int. Cl. D6—04

U.S. Cl. D26—5 C

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of the instrument cabinet of the present invention showing the left, front and top sides having the flip-top in the closed position;

FIG. 2 is a perspective view of the instrument cabinet shown in FIG. 1 showing the rear, left and top sides thereof;

FIG. 3 is a side elevation view of the left side of the instrument cabinet shown in FIG. 1 with the opposite side being a mirror image thereof;

FIG. 4 is an elevation view of the front side of the instrument cabinet shown in FIG. 1;

FIG. 5 is an elevation view of the rear side of the instrument cabinet shown in FIG. 1;

FIG. 6 is a top plan view of the instrument cabinet shown in FIG. 1;

FIG. 7 is a perspective view showing the left, front and top sides of the instrument cabinet shown in FIG. 1 having the flip-top shown in the raised position;

FIG. 8 is a perspective view of the rear, left and top sides of the instrument cabinet shown in FIG. 7;

FIG. 9 is an elevation view of the left side of the instrument cabinet shown in FIG. 7 with the opposite side being a mirror image thereof;

FIG. 10 is an elevation view of the front side of the instrument cabinet shown in FIG. 7;

FIG. 11 is an elevation view of the rear side of the instrument cabinet shown in FIG. 7; and

FIG. 12 is a top plan view of the instrument cabinet shown in FIG. 7.

I claim:

The ornamental design for a flip-top instrument cabinet, as shown and described.
